UNITED STATES PATENT OFFICE

166,124

SCALP MASSAGE BRUSH OR SIMILAR ARTICLE

Woodrow W. Pearce, Los Angeles, Calif.

Application September 25, 1950, Serial No. 12,332

Term of patent 14 years

(Cl. D83—1)

To all whom it may concern:

Be it known that I, Woodrow W. Pearce, a citizen of the United States, residing in Los Angeles, county of Los Angeles, State of California, have invented a new, original, and ornamental Design for a Scalp Massage Brush or Similar Article, of which the following is a specification, reference being had to the accompanying drawing, forming part thereof.

Figure 1 is an exploded perspective view of a scalp massage brush or similar article, showing my new design;

I claim:

The ornamental design for a scalp massage brush or similar article, substantially as shown.

WOODROW W. PEARCE.
